(57) **CLAIM**

We claim the ornamental design for a sandwich, as shown and described.

DESCRIPTION

FIG. 1 is a front/top perspective view of a first embodiment of the sandwich (ripples on one surface of the crimp);

FIG. 2 is a top plan view thereof;

FIG. 3 is a bottom plan view thereof;

FIG. 4 is a front elevational view thereof;

FIG. 5 is a rear elevational view thereof, for which a front side elevational view would be a mirror image; and

FIG. 6 is a left side elevational view thereof, for which a right side elevational view would be a mirror image thereof.

FIG. 7 is a front/top perspective view of a second embodiment of the sandwich (stippled; ripples on one surface of the crimp);

FIG. 8 is a top plan view thereof;

FIG. 9 is a bottom plan view thereof;

FIG. 10 is a front elevational view thereof;

FIG. 11 is a rear elevational view thereof, for which a front side elevational view would be a mirror image; and,

FIG. 12 is a left side elevational view thereof, for which a right side elevational view would be a mirror image thereof.

The stippling in FIGS. 7-12 represents a contrast in appearance between the second embodiment of the sandwich and the first embodiment of the sandwich shown in FIGS. 1-6. FIGS. 1-12 are identical to FIGS. 7-12 except for the stippling.

The broken lines immediately adjacent the shaded areas represent the bounds of the claimed design, while all other broken lines are directed to environment; the broken lines form no part of the claimed design.
